Primary Examiner — Ryan Harvey*(74) Attorney, Agent, or Firm* — Kirk A. Buhler; Buhler & Associates(57) **CLAIM**

The ornamental design for an elliptical stepper exercise machine, as shown and described.

DESCRIPTION

FIG. 1 is a rear perspective view for an elliptical stepper exercise machine showing my new design;

FIG. 2 is a right side view thereof;

FIG. 3 is a rear view thereof;

FIG. 4 is a front view thereof;

FIG. 5 is left side view thereof;

FIG. 6 is a bottom view thereof;

FIG. 7 is a top view thereof; and,

FIG. 8 is a front perspective view.

The broken line showing of portions of the elliptical stepper exercise machine depicts environment and forms no part of the claim.

1 Claim, 8 Drawing Sheets(56)
